(57) **CLAIM**

The ornamental design for a pistol grip tumbler handle, as shown and described.

DESCRIPTION

FIG. 1 is a top perspective view of a pistol grip tumbler handle showing my new design;

FIG. 2 is a bottom perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof; and,

FIG. 9 is a top perspective view thereof, showing the pistol grip tumbler handle holding a beverage container.

The broken lines showing of a beverage container in FIG. 9 are included for the purpose of showing environmental structure and form no part of the claimed design.
